WILLIAM A. SCHUMANN AND JERRY M. HUGHES, OF WATERTOWN, WISCONSIN

THREAD LUBRICATOR

Application filed July 30, 1929. Serial No. 382,226.

This invention relates to sewing machines and more particularly to a thread lubricator adapted to be attached to a sewing machine of a conventional construction. When 5 shoes are being sewed, it often happens that the thread will break thereby making it necessary to rethread the machine and also causing a waste of thread in addition to loss of time. Attachments have been used by means 10 of which a cake of soap may be supported in such a position that the thread will bear against the soap in order to cause soap to be applied to the thread and lubricate the thread and make it tougher. This is only satisfactory for a short length of time as the thread 15 soon wears the soap to such an extent that the soap is no longer properly applied to the thread.

Therefore, one object of this invention is 20 to provide an attachment whereby liquid soap may be applied to the thread and proper lubrication of the thread thereby assured.

Another object of the invention is to provide an attachment of this character in which 25 the thread may be passed through a cup containing a pad of absorbent material, such as a sponge, saturated with liquid soap by means of which the thread is to be lubricated.

Another object of the invention is to so 30 form the cup that the liquid soap with which the sponge in the cup is saturated will gravitate towards a thread passage in the bottom of the cup and thereby insure proper application of soap to the thread.

Another object of the invention is to provide an improved means for supplying liquid 35 soap to the cup and to allow flow of soap to the cup to be controlled.

The invention is illustrated in the accompanying drawings, wherein

Figure 1 is a perspective view of a conventional form of sewing machine with the improved thread lubricator applied thereto,

Fig. 2 is an enlarged view showing the lubricator partially in vertical section and partially in elevation,

Fig. 3 is a vertical sectional view taken on the line 3—3 of Fig. 2, and

Fig. 4 is a transverse sectional view

through the soap container taken on the line 4—4 of Fig. 2.

This improved lubricator is intended for use in connection with a sewing machine of a conventional construction, and in Fig. 1 there has been shown a sewing machine 1 of a type ordinarily used for sewing shoes. The lubricator is applied to the sewing machine, as shown in this figure, and includes a cup 2 supported in such a position that the thread 3 passes through the cup before it reaches the needle and will have liquid soap applied to it. The cup 2 is formed of metal and includes a rear wall 4, front wall 5 and end walls 6, one of which is extended to form an arm or bracket 7. This arm carries a boss 8 extending from its inner side face and through the boss is formed an opening 9 through which a fastener 10 may be passed in order to secure the arm firmly against the sewing machine with the cup supported in front of the machine in such a position that the thread will pass downwardly through the cup. The front wall has its lower portion curved rearwardly, as shown in Fig. 2, to form a bottom 11 for the cup and the bottom terminates in spaced relation to the rear wall thereby providing a passage 12 through which the thread passes. It should be noted that the free end of the bottom is rolled forwardly, as shown at 13, thereby eliminating an edge against which the thread might bear and be worn through. Since the bottom of the cup, extends downwardly towards the rear wall, the cup tapers towards the thread passage and, therefore, liquid soap with which the sponge or absorbent pad 12 is saturated will gravitate toward the thread passage and proper lubrication of the thread will be assured.

The reservoir or receptacle 14 for the liquid soap consists of a metal receptacle preferably of a cylindrical shape and having its upper portion threaded so that a cap 15 may be securely but releasably held in place. This receptacle is supported in a vertical position by a bracket or arm 16 consisting of a strip of metal secured about the receptacle, as shown at 17, and projecting therefrom so that it may be firmly secured against the sewing

machine by a fastener 18 passed through an opening 19 near its free end. A tube 20 leads from the bottom of the receptacle 14 and terminates in a horizontal end portion 21 which extends transversely through the cup above the sponge or pad 12 and is formed with outlet openings 22 in its upper portion through which the liquid soap may escape and flow down onto the sponge. By having 10 the openings formed in the upper portion of the tube there will be no danger of these openings becoming clogged by the sponge or by sediment which may gather in this portion of the tube. A valve 24 is provided intermediate the length of the tube so that the flow of liquid soap may be controlled. It will thus be seen that a small quantity of soap may be continually applied to the sponge or the valve normally left closed and only opened 20 when necessary.

When this attachment is in use, it is applied to the sewing machine, as shown in Fig. 1, and the thread is passed through the cup, as shown in Fig. 2. The valve is opened 25 in order to allow soap to flow onto the sponge and thoroughly saturate it and it may then be closed or left open sufficiently to allow a small quantity of soap to be continually fed to the sponge. The soap gravitates towards 30 the bottom of the sponge and this assures proper application of the soap to the thread. In view of the fact that the soap is liquid instead of a cake it will always be properly applied to the thread and even if the thread 35 should wear the sponge this will not prevent the soap from being applied to the thread. We have, therefore, provided a device by means of which liquid soap may be applied to the thread of a sewing machine in order 40 to properly lubricate it at all times.

Having thus described the invention, we claim:

A thread lubricator comprising a cup, a 45 pad of absorbent material in said cup to be saturated with liquid absorbent, the said cup being open at its top and having a thread passage in its bottom, means to support the cup in an operative position, a container, means to support the container in place above 50 the cup, a tube leading from the lower end of said container and having a portion extending horizontally into said cup above the pad and formed with outlet openings spaced from each other longitudinally of the said portion, 55 and means to control flow of lubricant through said tube.

In testimony whereof we affix our signatures.

JERRY M. HUGHES. [L. S.]
